UNITED STATES PATENT OFFICE.

ALOYSIUS WAYDITCH, OF NEW YORK, N. Y., ASSIGNOR OF ONE-HALF TO HERMAN MILLER, OF NEW YORK, N. Y.

DRAFTING INSTRUMENT.

1,290,812.

Specification of Letters Patent.

Patented Jan. 7, 1919.

Application filed June 26, 1917. Serial No. 176,998.

To all whom it may concern:

Be it known that I, ALOYSIUS WAYDITCH, a subject of the Emperor of Hungary, and a resident of the county of Bronx, city and State of New York, have invented 5 a certain new and useful Drafting Instrument, of which the following is a specification.

My invention relates to a new and improved drafting instrument, and more particularly to an instrument for drawing ellipses or ovals.

The objects of my invention are to produce an instrument of low cost, and one 15 which may be readily adjusted to make ellipses or ovals of different sizes.

These and further objects will more fully appear in the following specification and accompanying drawings considered together or separately.

In carrying out my invention, I provide a spindle 1 having a cylindrical portion 2 at its center, and non-cylindrical portions 3, and 4,—one on each side of the central portion. The upper extremity of the spindle is rotatable relatively to the spindle and removable therefrom. The lower extremity of the spindle is tapered to form a needle 6 by means of which the instrument is caused 20 to engage the paper. Adjustably carried on the portion 4 of the spindle is a needle point 7 pivoted in a bracket 8.

Adjustably carried on the cylindrical part of the spindle is an abutment 9 secured in place by a set screw. A tube 10 is loosely mounted on the cylindrical part of the spindle and is supported in position by the abutment 9. Pivoted to the tube 10 are two arms 11 and 12. These arms are composed 25 of parallel strips, each provided with a longitudinal slot 11^a, 12^a. The ends of the arms are joined by a bar 13 which acts in the same manner as a parallel ruler. A standard 14 is carried between the plates forming 30 the arms 11 and 12. The standard is provided with trunnions, each of which carries blocks 15 slidable in the slots 11^a and 12^a.

The bar 13 and the standard 14 is each provided with a recess in which is pivoted 35 a bearing 13^a and nut 14^a respectively. Engaging the nuts is a screw 16 held against

longitudinal movement in the bearing 13^a and with its threaded portion engaging the nut 14^a on the standard. When the screw is rotated by means of its milled head, the 55 standard 14 will be moved toward or away from the bar 13.

Adjustably carried on the lower end of the standard 14 is a fitting 17, the lower portion of which is slotted, and two arms 18, 18 are pivoted at separate points within the slot. The lowermost arm 18 is provided with a screw-threaded extension 19 which carries a milled edge nut 20, which is adapted to engage the lower circular end 21 of the 60 fitting. The opposite ends of the arms 18, 18 are pivoted to a member 22 in such a manner as to cause the member to act in the same manner as a parallel ruler. Adjustably carried by the member 22 is a marking 65 point 23 which may be a pen, pencil, scribe or the like.

Removably and adjustably carried on the non-circular part 3 of the spindle is an elliptical templet 24 and adapted to engage with 70 the edge of said templet is an arm 25 carried by the arm 11 which is thereby held in a certain inclined position relatively to the standard. This inclined position will vary 75 accordingly as the arm 25 engages a point on the edge of the templet, more or less removed from the axial line of the standard which is also the center of the templet, provided the latter is a symmetrical figure.

I desire to have it understood that the 85 templet may be of shapes other than elliptical, as for example oval.

The operation is as follows:

When it is desired to produce an ellipse, an elliptical templet is placed in position on 90 the part 3 of the standard, and the needle point is so adjusted that its lower extremity is on a level with the point of the needle 6 and to some distance to one side thereof. The point 7 must be positioned relatively to 95 the point 6 and the templet 21, so that the points 6 and 7 may rest on a line forming the long diameter of the ellipse to be inscribed.

The line of the long diameter is now 100 drawn on the paper and bisected. The point 6 is placed at the center of the line, and the

point 7 on the line at one side thereof, with the standard perpendicular to the surface of the paper. The arms 11 and 12 are swung around until they are in line with the line 5 on the paper. The screw 16 is now manipulated to bring the pen point to one end of the line. The templet is now positioned upon the part 3 of the spindle with one of its longest radii resting against the arm 25. 10 In order that the paper may not be soiled by ink running from the pen, the latter will be raised, by hand, slightly above the paper during the above described adjustment. When the pen is so raised the nut 20 will be 15 screwed up against the part 21 so as to hold the pen above the paper. When the pen is in proper position relatively to the line on the paper, the nut is released from the part 21 and the pen allowed to rest at the 20 proper point on the paper. The tube 10, and with it all the parts of the device, except the spindle and the parts secured thereto, is now rotated about the center of the spindle with the arm 25 always engaging 25 the edge of the templet. The result will be, a perfect ellipse will be drawn on the paper.

The size and relative diameters of the drawn ellipse may be varied without the necessity of employing a different templet 30 for each size.

By manipulating the screw 16, adjusting the pen in the member 22, and adjusting the position of the fitting 17 on the standard 14, an ellipse of any size within the limits 35 of the device may be inscribed. It will be understood that as the angles of the arms 11 and 12 are changed by moving their outer ends vertically relatively to the point of the pen, the templet must be raised or lowered so that one of its long ends will engage 40 the arm 25 when the pen is at the end of a long diameter of the figure to be drawn.

I desire it understood that my invention is not confined to the particular form of 45 apparatus herein shown and described, and, therefore, I claim broadly the right to employ all equivalent instrumentalities coming within the scope of the claims, and by means of which objects of my invention are attained, and the new results accomplished, 50 as herein set forth, as it is obvious that the particular embodiment herein shown and described is only one of many that can be employed to attain these objects and accomplish these results.

In accordance with the provisions of the patent, statutes, I have described the principle of my invention together with the apparatus which I now consider to represent 60 the best embodiment thereof, but I desire to have it understood that the apparatus shown is merely illustrative and that the invention can be carried out in other ways.

Having now described my invention, what

I claim and desire to secure by Letters Patent is:

1. A drafting instrument having a spindle, a sleeve rotatable on the spindle, a pair of arms pivoted to the sleeve, said arms being movable in parallel relation with each other, an extension carried by one of the arms, a standard carried by the arms, a scribe carried by the standard, and a templet adjustably carried by the spindle, and engaging the extension, whereby the scribe may be caused to rotate about the axis of the spindle in a non-circular path. 75

2. A drafting instrument having a spindle, a sleeve rotatable on the spindle, a pair of arms pivoted to the sleeve, said arms being movable in parallel relation with each other, an extension carried by one of the arms, a standard carried by the arms, means for adjusting the standard relatively to the arms, a scribe carried by the standard, and a templet adjustably carried by the spindle and engaging the extension, whereby the scribe may be caused to rotate about the axis of the spindle in a non-circular path. 80

3. A drafting instrument having a spindle, a sleeve rotatable on the spindle, a pair of arms pivoted to the sleeve, said arms being movable in parallel relation with each other, an extension carried by one of the arms, a standard carried by the arms, a screw for adjusting the standard relatively to the arms, a scribe carried by the standard, and a templet adjustably carried by the spindle and coöperating with the extension, whereby the scribe may be caused to 90 rotate about the axis of the spindle in a non-circular path. 95

4. A drafting instrument having a spindle, a sleeve rotatable on the spindle, a pair of arms pivoted to the sleeve, said arms being movable in parallel relation with each other, an extension carried by one of the arms, a standard carried by the arms, a scribe adjustably carried by the standard, and a templet adjustably carried by the 100 spindle and engaging the extension, whereby the scribe may be caused to rotate about the axis of the spindle in a non-circular path. 105

5. A drafting instrument having a spindle, means for supporting the spindle perpendicular to a surface, a sleeve rotatable on the spindle, means for adjusting the sleeve on the spindle, a pair of slotted arms pivoted to the sleeve, an extension carried by one of the arms, a link connecting the 110 free ends of the arms, a standard supported by the arms, a screw carried by the link and engaging the standard whereby the latter may be moved in the slots, an adjustable fitting carried by the standard, fingers pivoted to the fitting, a member carried by the fingers, a scribe adjustably carried by the member, and an adjustable templet carried 115

by the spindle and engaging the extension as the latter is rotated about the axis of the spindle, whereby the scribe may be caused to rotate about the axis of the spindle in a non-circular path, and whereby the path of the scribe may be varied relatively to the path of the spur around the temple.

This specification signed and witnessed this 21st day of June, 1917.
